UNITED STATES PATENT OFFICE.

AMBROSE O. BARTHOLOMEW, OF ALLENTOWN, PENNSYLVANIA.

PHONOGRAPH-HORN NECK.

Application filed September 21, 1922, Serial No. 589,713.

To all whom it may concern:

Be it known that I, AMBROSE O. BARTHOLOMEW, citizen of the United States, residing at Allentown, in the county of Lehigh and State of Pennsylvania, have invented certain new and useful Improvements in Phonograph-Horn Necks, of which the following is a specification.

This invention relates to phonographs and has special reference to a horn connection for devices of this description.

In the construction of phonographs one important object to be attained is the prevention of sound waves by vibration in parts of the casing of the machine which tend to destroy the purity of the tone and timbre sought to be reproduced. Experience has shown that one of the most frequent causes of bad reproduction lies in the connection between the tone arm and the amplifying horn in phonographs since at this point there is not only a considerable looseness which tends to produce improper vibrations but the metallic character of this portion of the device itself sets up certain vibrations in the material of the connection which produce injurious results.

One important object of the present invention is the provision of a novel character of connection between the tone arm and the amplifying horn, which connection will practically form a portion of the amplifying horn itself and which will prevent all improper vibrations of the connection itself as well as to dampen or absorb any vibrations produced by looseness in the connections between the connector end of the tone arm and amplifying horn, respectively.

A second important object of the invention is the provision of means of novel character to prevent setting up of such vibrations by providing a connector of sufficient mass and lack of elasticity as to dampen and absorb any vibrations set up therein by the sound waves passing therethrough so that these vibrations are not transmitted to the woodwork of the casing.

With the above and other objects in view as will be hereinafter apparent, the invention consists in general of certain novel details of construction and combinations of parts hereinafter fully described, illustrated in the accompanying drawings and specifically claimed.

In the accompanying drawings like characters of reference indicate like parts in the several views, and:

Figure 1 is a vertical median section through a phonograph showing the connection constructed in accordance with this invention.

Figure 2 is a section on the line 2—2 of Figure 1.

Figure 3 is a detail perspective view of the connection removed from the casing.

This connection consists of a single massive block 10 of cementitious material, the material employed being preferably plaster of Paris with a mixture of about 10% of ordinary cement. This material is molded into a rectangular form and through the block extends a sound passage which enters the upper end of the block as at 11 by a relatively small round opening corresponding in size to the measure of the end 75 of the tone arms 12. The passage through the block curves downwardly and forwardly from this opening 11, expanding both vertically and laterally and terminating in an opening 13 on the front side of the block 80 which is considerably larger than the opening 11 and is of trapezoidal form. This opening 13 corresponds with the minor end of the amplifying horn 14 of the phonograph. In Figure 1 it will be seen that the phonograph casing 15 is divided by a partition 16 into an upper chamber 17 wherein is located a turn table 18 and tone arm 12 and a lower chamber 19 wherein is located the amplifying horn 14 and motor 20. This 90 lower chamber is divided into a front and rear compartment by a partition 21 and the rear compartment is provided with partitions 22 so that the block 10 can just fill the space between these partitions, the partition 21 and back wall 23 of the phonograph. Furthermore, the height of the block is such as to correspond to the height of the compartment wherein it fits. With this construction, it will be observed that this 95 massive, practically non elastic connection, absorbs without transmission to the wooden casing vibrations produced by sound waves in the passage except those vibrations in the air which produce effective sound waves for 100 amplification by the horn. In order to render the surface of the opening through the block smooth the walls of said opening are

105

coated as at 24 with some material, as shellac, which will give a glassy, smooth surface.

By means of this massive block it will also be noted that no vibrations due to the block itself will affect the air in the passage and consequently no injurious sound waves will be produced by vibration of the block.

There has thus been provided a simple and efficient device of the kind described and for the purpose specified.

Having thus described the invention what is claimed as new, is:—

A phonograph horn neck comprising a substantially dead non-resilient and non-vibrant cast cementitious body block having

a single curved sound passage increased in cross sectional area from the inlet end thereof to the outlet end thereof whereby the core used in the molding operation of the block may be readily withdrawn, said passage being trapezoidal at the outlet end, the solid volume of the body being greatly in excess of that of the opening whereby no sympathetic tones of the body due to wall vibrations will occur.

In testimony whereof I affix my signature in presence of two witnesses.

AMBROSE O. BARTHOLOMEW.
